SHINGLE GROOVING MACHINE

Lyman E. Rackleff, Los Angeles, Calif.

Application May 24, 1948, Serial No. 28,859

8 Claims. (Cl. 144—136)

1

This invention relates to a shingle grooving machine.

Heretofore it has been the common practice, wherever necessary to cut a shingle through on a bias to prepare it for being applied to roof gables or valleys or to the upper edge portions of gable roofs to use a saw or hatchet to cut through the shingle with a view to shaping it properly for the intended use. Doing this not only requires the expenditure of considerable portions of the shingler's time, but also (particularly when a hatchet is used) often results in producing ragged, uneven cut edges which detract from the streamline, attractive appearance of the applied roof.

When a shingle is cut to the desired size and shape by a hatchet, the chopped off portion is wasted, but it may be used, for example, in the valley of a roof if cut off with a saw; but when sawed off, no two sawed-off pieces will ever be precisely alike in size and shape.

Using irregularly shaped, split or cracked shingles in roof valleys is objected to by the Federal Housing Administration, in other words, this department of the government frowns upon using in roof valleys shingles salvaged from roof hips in the manner heretofore attempted.

With a view to overcoming the foregoing objectionable features and defects in present shingling methods, it is an object of this invention to make it possible to apply standard wood shingles to a roof in an easier and more rapid manner.

Another object is to enable the roofer to conserve material that it was formerly considered necessary to waste, and at the same time to make it possible to apply a better roof.

A more specific object is to provide an improved means for shaping shingles to fit into roof valleys and for use in finishing of peak portions of roofs in a more streamline, workmanlike manner.

A further specific object of the invention is to provide a portable, shingle-grooving instrument or machine which the roofer can mount upon the sheathing of a roof and which he can use from time to time, while working on the roof, to groove or partially cut through, shingles along lines of intended cleavage, so that shingles so grooved can be quickly prepared for fitting into roof margins bordering valleys and peak portions of the roof, which prepared shingles will be particularly serviceable for use upon the angular portions of hip and gable roofs.

2

Other objects, advantages and features of invention will hereinafter appear.

Referring to the drawings, wherein is shown a preferred embodiment of the invention as now being practiced in the trade,

Fig. 1 is a side elevation of the device operatively situated upon a fragment of a sectioned roof being shingled, with a shingle in the device positioned for having performed upon it the grooving operation. In this view portions of the device are broken away in order to disclose underlying structure.

Fig. 2 is an elevation looking at the right hand side of Fig. 1, the roof being omitted, an upper fragment of the device being broken away to show underlying structure.

Fig. 3 is a transverse section on line 3—3 of Fig. 1, the shingle being omitted.

Fig. 4 is a fragmentary, enlarged section on line 20 4—4 of Fig. 3.

Fig. 5 is a view, partly in plan and partly in section, the sectioned portion of the view being on line 5—5 of Fig. 4.

Fig. 6 is an enlarged, fragmentary section on line 6—6 of Fig. 1. Parts of the structure in front of the blades are broken away.

Fig. 7 is a section taken on angular line 7—7 of Fig. 6.

Fig. 8 is a vertical section on line 8—8 of Fig. 30 6, a part broken away in Fig. 6 being included in the view.

Fig. 9 is a perspective view of the shingle shown in Fig. 1, after grooving.

Fig. 10 is a transverse section on line 10—10 of Fig. 2.

Fig. 11 is a fragmentary perspective view of the shingle-carrying cradle.

Referring in detail to the drawings, in Fig. 1 the device is shown mounted upon a roof having 40 sheathing boards 12 carried by rafters 13. The device comprises a pair of parallel, upstanding rods 14 which form parts of an upstanding guide frame. Said rods have their lower end portions secured in any suitable manner to a base plate 15, as for example, by being fitted into apertures through said plate and being welded in said apertures, as shown in Fig. 4. The upper end portions of said rods are secured in a parallel, spaced apart relation by means of a U-shaped, strap metal handle member 16, with the outer end portions of the arms of said U overlying the ends of said rods 14 and secured to them by means of screws 17.

Said base plate 15 is welded to the horizontal flange 18 of an angle member 19. Said angle member, internally of its angle, is welded to a sleeve 20, said sleeve being loosely mounted upon a shaft 21. Said shaft is secured against rotation by being welded in bores 22 of bracket arms 23. Said bracket arms are tapered toward their upper ends (see Fig. 1.), where said bores are located. Said shaft 21 bridges the space between said bracket arms and projects outwardly slightly beyond them where welds 21w are applied to secure it to said bracket arms. Each of said bracket arms has a rectangular base portion 24, said base portions being welded to a tie plate 25. Said tie plate has its outer edge portions abutting against and welded to the inner edge portions of a pair of parallel foot plates 26. The outer edge portions of the rectangular foot flanges 24 are, in turn, welded to the upper faces of said foot plates 26, the latter having rectangular hooked, downwardly directed end portions 27, which may be hooked over the sheathing strips 12 of the roof to maintain the device in its operative position upon a roof.

The framework, of which the aforesaid rods 14 form a part, is maintainable in various tilted positions by means of a plurality of threaded bores 28 located in the vertical leg of the aforesaid angle bar 19 at various longitudinally spaced points along the length of the aforesaid sleeve 20 and shaft 21. Said bores 28 are alined with bores 29 tapped into the aforesaid sleeve 20, and also alined with diametrically reduced bores 30 in said shaft 21, and are in radial alinement both with the tapped bores 29 of said sleeve and the bores 28 of said vertical leg. Said bores 28, three of which are shown, enter radially into the aforesaid leg, sleeve and shaft at different points in relation to the circumference of said sleeve and shaft.

The swingable frame structure just described is maintained in various adjusted positions by means of an L-shaped pin 31 having the end portion of its longer limb 32 diametrically reduced to seat in the bores 30 of said shaft, and adjacent to said diametrically reduced end portion said pin is provided with threads to engage the alined threaded bores 28 and 29 already mentioned.

Upon the aforesaid parallel frame rods, 14 is mounted, a vertically reciprocatory frame 36 which carries a pair of shingle-grooving knives 37 and 37a, the mounting means for which will now be described. In Figs. 6 and 7 said mounting means is shown as comprising twin units 38 and 39. Each of these units is shown as consisting of two plates 41 and 42 bolted together in a face to face manner, said plate 42 having spot-welded to it a sleeve 43 which reciprocates along one of the rods 14 during the operation of the shingle-grooving knives. The other plate 41 has welded to it a metal strip 44 which is T-shaped in cross section, the stem of the T, in turn being welded along its outer edge to the thickened lower end portion 45 of a vertically extending rectangular bar 46. Said bar 46 has a transverse groove 47 in which is adjustably seated the blade 37 of said opposed cutting blades, said blade being held in place by an overlying strap 49. Figure 8 held abuttingly thereagainst by means of bolts 50 extending through said strap 49 and being tapped into said bar 46. The other twin frame member unit 39, being constructed the same as the unit already described is lettered in the same way except for the addition of the letter "a" to the reference numerals used. The twin, elongated cutter blades 37, 37a are shown provided with rounded,

opposed, adjacent cutting end portions 37x to groove the shingles in a smoother, more efficient manner. The lower end portions of the blade-supporting bars 46 are adjacently rounded at 45x so as to cause them more readily to straddle the shingles preparatory to the operation of the cutters on the latter.

A shock absorbing spring 51 is coiled around the lower end portion of each rod 14, said springs seating upon the plate 15 to cushion the down-stroke of the cutter-carrying carriage.

The aforesaid vertically reciprocatory, cutter-carrying frame 36 is manually moved up and down along the aforesaid rods 14 by means of a handle structure comprising at the top a horizontal handle proper 55 consisting of a short bar the ends of which are internally welded to the upper portions of parallel, spaced apart plates 56, said plate portions preferably being tapered toward the top and provided with rounded upper extremities, as shown. Spaced subjacent to said handle bar 55 is a transverse brace plate 57 which runs from side to side of the handle forming structure bridging the space between said plates 56 a considerable distance above their lower ends. The lower end portions of said plates 56 are internally united to each other by a rectangular, strap metal frame 60. The lower ends of said plates 56 project slightly below the ends of said frame 60 and within the angular corner thus formed at each side of the device abut the upper ends of paired strap metal braces 61, each of these four braces being externally and internally spot welded in this position as indicated in Figs. 1 and 2 at 61w. The lower end portion of each of said braces 61 is spotwelded at 61x to the aforesaid members 44 and 45 (see Fig. 2).

In Figs. 1 and 11 is shown a swingable cradle structure 65 adjustably to support the shingle 66 while being operated upon by the aforesaid cutters. This structure comprises a shorter saddle member 67 upon which is seatable the butt end portion of the shingle, and a longer saddle member 68 to have seated upon it one of the long edge portions of the shingle. These saddle members are similarly constructed, the member 67 consisting of an elongated plate bent along its mid-width in such a way as to provide a grooved shingle-holding part 67a having at each side an outwardly inclined lip portion 67b to aid the workman in guiding the shingles into said grooved part. Likewise the saddle member 68 has a grooved part 68a and shingle-guiding lips 68b.

Said saddle members 67 and 68 are respectively rigidly secured, by welding or otherwise, to mounting bars 70 and 71 of a one-piece saddle-carrying frame, or cradle, which also comprises twin end bars 72. The aforesaid base plate 15 has welded to each of opposite side portions of its upper face an upstanding arm 73. Said arms 73 have screwthreaded apertures through their upper end portions to have screwed into them T-shaped manually operable clamping screws 74 which pass through the apertured end plates 72 of the aforesaid saddle-carrying frame.

When the shingler arrives at the job he will take the device onto the roof and will apply its basal hooks 27 to the sheathing to anchor the device in its operative position in the manner illustrated in Fig. 1. Thereupon he will adjust the frame rods 14 to an approximately vertical position, in which position he will secure them by screwing the diametrically reduced end portion of angular pin 31 into the proper bore provided therefor in the shaft 21. Then he will adjust the

shingle-cradle 65 (comprising members 67 and 68) to the proper angular, shingle supporting position, securing it in that position by down-screwing its manually operable T-shaped screws 74. It will then only remain to insert a typical shingle 66 into the grooves provided for it in the saddle members 67 and 68 of the cradle 65 preparatory to proceeding to make opposed grooves 66a in the shingle, by manually forcing downward the frame 36 which carries the cutters 37, 37a, it being understood that said frame 36 was previously elevated to clear the way for placing the shingle in said saddle members.

The handle 16, in addition to joining to each other the upper end portions of the guide rods 14, serves as a handle usable to carry the device from place to place.

When the device has once been stationed upon a roof and the aforesaid frame rods 14 thereof adjusted to extend vertically regardless of the pitch of the roof, it will not, in this respect, be changed again while work is being done on that particular roof, but assuming that occasion demands that the grooves be made across the face of the shingles to adapt them to use on a different ridge or valley, all that it is necessary to do is to loosen the T-shaped screws 74, swing the cradle 65 to the proper angle, and then retighten said screws.

In the operation of the device the shock absorbing springs 51 reduce the shocks caused by the downward movements of the carriage 36 and thus make the operation of the device less fatiguing to the workman.

After the shingles have been grooved by the device, their grooved part can quickly and easily be manually broken across to provide shingle fragments of the predetermined size and shape.

It should be understood that the present disclosure is for the purpose of illustration only and that this invention includes all modifications and equivalents which fall within the scope of the subject matter claimed.

I claim:

1. In a shingle grooving machine, mounting means attachable to a roof being shingled, a frame mounted upon said mounting means, a shingle-carrying cradle mounted upon said frame to support a shingle in a vertical plane, and a carriage vertically reciprocable upon said frame and carrying opposed, parallel laterally spaced cutters positioned simultaneously to groove opposite faces of a shingle mounted in said cradle during manual reciprocation of said carriage, the grooving operation thus performed upon the shingle leaving a fragile web for subsequent severance of the shingle between the opposed grooves formed therein.

2. A device of the kind described comprising a basal portion provided with means to anchor it to the sheathing of an inclined roof, a cradle mounted upon said basal portion and having a saddle in which a shingle is fittable, guide means mounted upon said basal portion in an upstanding relation to the latter, a carriage manually reciprocable up and down upon said guide means, and a cutter mounted upon said carriage in a position to groove a shingle supported in said saddle when said carriage is moved downwardly.

3. The subject matter of claim 2 and, said saddle having diverging upwardly directed lip portions to guide downwardly inserted shingles into it.

4. In a shingle grooving machine, mounting means attachable to a roof being shingled,

elongated guide means upstanding from said mounting means; a carriage manually reciprocable along said guide means, a pair of opposed, adjacent laterally spaced cutters mounted upon said carriage with cutting edges directed toward each other, a cradle supported by said mounting means and furnished with a two-part saddle in which to support a shingle so as to maintain the latter extending in a vertical plane in position for having its opposite faces grooved with a pair of aligned registering grooves by said cutters when said carriage is moved downwardly, each of said two-parts of said saddle having in it an upwardly facing groove to receive an edge portion of a shingle, said grooves extending at substantially a right angle to each other.

5. In a shingle grooving machine, mounting means attachable to a roof being shingled, a frame mounted upon said mounting means, means positioned between said mounting means and said frame to adjust the latter at various upstanding inclinations in relation to the former, a shingle carrying cradle mounted upon said frame to support a shingle in a vertical plane, and a carriage vertically reciprocable upon said frame and carrying opposed, parallel laterally spaced cutters positioned simultaneously to groove opposite faces of a shingle mounted in said cradle, during manual reciprocation of said carriage, the grooving operation thus performed upon a shingle leaving a fragile web for subsequent severance of the shingle between the aforesaid grooves formed therein.

6. A device of the kind described comprising a basal portion, a frame carrying elongated guide means mounted upon said basal portion in an upstanding relation to the latter, a shingle carrying cradle mounted upon said frame, means associated with said basal portion to swingably adjust said frame and guide means in relation thereto, means positioned between said basal portion and said frame releasably to lock the latter in various adjusted positions in relation to the former, a carriage manually reciprocable up and down upon said guide means, and a cutter mounted upon said carriage in a position to groove, during its downward movement, a shingle supported in said cradle.

7. In a shingle grooving machine, mounting means supportable upon a roof being shingled, said mounting means comprising a base furnished with paired upstanding bracket arms, a shaft secured rigidly to and spanning the space between the upper end portions of said bracket arms, a sleeve loosely mounted upon said shaft, a frame structure to which said sleeve is meditately secured, so that said frame structure and sleeve are together swingably adjustable in relation to said shaft, there being a plurality of paired radially and longitudinally spaced bores extending diametrically into said sleeve and diametrically into said shaft, the bores of said sleeve being alinable with the bores of said shaft, a pin insertable within the alined bores to maintain said frame structure upstanding at various inclinations in relation to said base, a shingle carrying cradle mounted upon said frame structure to support a shingle in a vertical plane, and a carriage vertically reciprocable upon said frame structure and carrying opposed, parallel laterally spaced cutters positioned simultaneously to groove opposite faces of a shingle mounted in said cradle, during manual reciprocation of said carriage, the grooving operation thus performed upon a shingle leaving a fragile web for sub-

sequent severance of the shingle between the aforesaid grooves formed therein.

8. The subject matter of claim 7, and the aforesaid means for immediately connecting said frame structure with said sleeve comprising an angular plate, a portion of which is abuttingly rigidly secured to a plate portion of said frame structure, said sleeve being rigidly secured to the internal angle of said plate.
